United States Patent Office.

WILLIAM O. HICKOK, OF HARRISBURG, PENNSYLVANIA.

Letters Patent No. 70,715, dated November 12, 1867.

IMPROVEMENT IN PAPER-RULING MACHINES

The Schedule referred to in these Letters Patent and making part of the same.

TO ALL WHOM IT MAY CONCERN:

Be it known that I, WILLIAM O. HICKOK, of Harrisburg, in the county of Dauphin, and State of Pennsylvania, have invented a new and useful Improvement in the Paper-Ruling Machine; and I do hereby declare that the following is a full, clear, and exact description of the construction and operation of the same, reference being had to the accompanying drawings, making a part of this specification, in which—

Figure 1 is a vertical transverse section, and

Figure 2 a plane or orthographic view of the said improvement applied to a ruling machine.

Like letters of reference indicating the same parts when in both figures—

In the operation of the ruling machine heretofore used, the paper therein is liable to "creep" or vary from the proper line of progression toward the pens, especially when the said paper has not a perfectly flat or even surface, and consequently a great deal of watchfulness and careful readjustments of the sheets of paper are required to prevent irregularities in the ruling; and the object of my improvement is to effectually provide against the occurrence of these objections.

My invention consists, substantially as hereinafter described, in the application of a stationary table or solid bearing surface, in the usual open space which is between the pen-cylinder and the feed-rolls.

Referring to the drawings, A B are the usual frame of the machine; C, the pen-cylinder, D D', the feed-rolls; D'', one of the web-supporting rolls; E, the paper-carrying web; F F, the paper-holding cords; G, the stationary table or solid bearing surface, and H a sheet of paper between F and G. The table G consists of a broad, stationary, unyielding support for that portion of the endless web E which moves along between the feed-rolls D D' and the pen-cylinder C. Its length corresponds with the length of the cylinder C; its upper surface is slightly curved transversely, its sides are parallel to each other, and the width of its upper surface such as causes it to nearly fill the usual space which is left between the upper sides of the small roll D'' and the pen-cylinder C, without touching either, when the said table G is fixed between them in such a position that its upper surface and the upper surfaces of the roll D'' and the pen-cylinder C will together afford a curved, rigid support for the web E and the cords F, as the latter move over them, substantially as represented in the drawings. The table G is rigidly secured in the described position by means of supporting-bars g' g', which rest in suitable bearings fixed on the inner sides of the two side rails a' b' of the frame A B, (see fig. 2.)

In the operation of the machine thus improved, the web E and the cords F which at any time may be moving across the table G, will necessarily be supported by the table in a steady or unyielding condition, and consequently the sheets of paper H which may have been fed between them by the rolls D D' D'' will be carried along to and under the usual pens, thereby precisely in the same relative positions in which they leave the two feed-rolls D D', thus avoiding the necessity of the watchfulness, delay, and readjustments heretofore required to detect and remedy the "creeping" of the paper.

The device is inexpensive of construction, can be easily applied to old machines, and is entirely effective for the purpose intended.

Having thus fully described my improvement in the ruling machine, what I claim as new, and of my invention, and desire to secure by Letters Patent, is—

The application thereto of a stationary table, G, so that it will operate in combination with the web E, cords F, and feed-rolls D D', substantially in the manner described and set forth for the purpose specified.

W. O. HICKOK.
